METHOD AND MACHINE FOR GROOVING
SHAVING GEARS

Ernest Wildhaber, Irondequoit, and Allan H. Candee and Winfred A. Witham, Rochester, N. Y., assignors to Gleason Works, Rochester, N. Y., a corporation of New York

Application November 25, 1936, Serial No. 112,733

22 Claims. (Cl. 90—15.1)

The demand for quieter and quieter gears has resulted in the past few years in ever-increasing use of the so-called shaving method as an auxiliary finishing operation in the production of high quality gears such as are intended for use, for instance, in automotive drives.

In gear shaving, the tool employed is of gear form and its teeth are gashed or grooved to provide cutting edges. The shaving operation is performed by meshing the gear to be shaved with the shaving gear and operating the two together as though they were a pair of meshing gears. In some instances, the gear to be shaved and the shaving gear are so meshed that a relative sliding motion is produced between them as they operate together. In other instances, the relative sliding movement is effected as an added motion. In still other instances, the work and shaving gear have a pure rolling motion in mesh and there is no relative sliding.

The present invention relates to a machine and method for grooving shaving gears and also to tools employable in the grooving of shaving gears. In particular, the invention relates to the grooving of shaving gears whose cutting edges are formed by grooves extending longitudinally in the sides of the teeth. More especially, the invention relates to the production of longitudinally curved tooth shaving gears which are of tapered gear form and of the non-generated or "Formate" type and intended for finishing spiral bevel and hypoid gears. In a still more specific aspect, the invention relates to the grooving of shaving gears of the type covered by the pending United States application of Winfred A. Witham, Serial No. 61,237, filed January 28, 1936.

One purpose of the present invention is to provide a very fast but relatively cheap and simple method of grooving shaving gears of the character described.

Another object of the invention is to provide simple, but efficient apparatus for carrying out said method.

A further object of the invention is to provide a method for grooving shaving gears which may be performed upon existing gear cutting machinery with but slight modification thereof.

Still another object of the invention is to provide a highly efficient form of cutting tool for the grooving operation.

Other objects of the invention will be apparent hereinafter from the specification and from the recital of the appended claims.

In the drawings:

Fig. 1 is a fragmentary side elevation of a

spiral bevel gear cutting machine of standard form as modified to practice the present invention, part of the machine being broken away and shown in section;

Figs. 2 and 3 are detail views taken at right angles to one another and showing parts of the mechanism for adjusting the cutter axially in the machine shown;

Fig. 4 is a diagrammatic sectional view illustrating the operation of grooving one side of the teeth of a spiral bevel or hypoid shaving gear with a cutter constructed according to one embodiment of this invention;

Fig. 5 is a view showing the grooving of the opposite side of the teeth of the shaving gear with a cutter of slightly modified form;

Fig. 6 is a cross-section on an enlarged scale of a shaving gear after the grooving operation is completed; and

Fig. 7 is a side elevation of one blade of a cutter such as might be employed in the grooving process.

In grooving shaving gears by the present invention a cutting tool is preferably employed which has a cutting edge formed by a plurality of alternate grooves and lands. Such a tool is capable of forming simultaneously a plurality of grooves and lands on the side of a tooth of the shaving gear as it is moved across the face of the gear from one end of the tooth to the other. For grooving spiral bevel and hypoid shaving gears the cutting tool preferably takes the form of a face-mill having a plurality of cutting blades whose side faces are provided with a plurality of grooves spaced in the direction of height of the blades. The grooves are produced in the side surface of the shaving gear by imparting a cutting motion to the grooving tool and feeding the tool sidewise into the tooth surface.

The sidewise or lateral feed movement may be effected in any suitable manner. In grooving a spiral bevel or hypoid shaving gear it is possible, however, to use a standard Spiral Bevel Gear Generating Machine with only a slight modification thereof to practice the present invention and such a machine has been illustrated in the accompanying drawings. To groove a shaving gear on this machine, the groove-cutting tool is mounted on the cutter spindle of the machine and a finish-cut spiral bevel or hypoid gear is mounted on the work spindle of the machine. The work may be rotated to feed the work laterally into the cutter, but preferably the work is held stationary on its axis during cutting and the lateral feed is produced by rotation of the cradle.

upon which the cutter is mounted. The rotary movement of the cradle produces a lateral feed movement between the grooving cutter and the work in a direction substantially perpendicular to a side surface of a tooth of the work.

After the grooves have been cut to the required depth in a side of a tooth of the work, the direction of rotation of the cradle is reversed to withdraw the grooving cutter sidewise from the 10 cut and at the end of the reverse movement of the cradle, the work is withdrawn relatively from engagement with the cutter and then the work is indexed to bring a new tooth surface of the work into position to be grooved. The grooving 15 cutter is then moved back into engagement with the work and the grooving cycle begins anew.

In the grooving of opposite side tooth surfaces of the work, the sidewise feed between the grooving cutter and the work is in opposite directions. 20 A cutter may be used that has opposite side-cutting edges and it may be readjusted relative to the work between the grooving of opposite sides of the teeth of the work or different cutters may be used for the grooving of the opposite sides of 25 the teeth.

Preferably between the grooving of successive corresponding sides of the teeth of the work, the grooving cutter is shifted a slight amount axially so that the grooves on the corresponding 30 sides of successive teeth of the tool gear may be displaced slightly and progressively with reference to one another. A shaving gear grooved in this manner will produce a smoother shaved surface on a gear being shaved.

35 The grooving cutter may have the grooves in the sides of its cutting blades formed in any suitable manner. Preferably, the grooves are cut into the sides of the cutting blades so that the sides of the grooves will extend in a direction parallel to the direction of feed of the tool, that is, for a face-mill type of grooving cutter, in a direction perpendicular to the axis of the cutter. With this construction, grooves may be cut into the 40 shaving gear whose sides are perpendicular to the side surfaces of the shaving gear. A shaving gear with grooves so formed will have a keen cutting action.

Where the feed of the grooving cutter into the side surface of the teeth of the shaving gear is 50 produced by rotation of a cradle upon which the cutter is mounted, it is preferable to maintain the side cutting edge of the grooving cutter parallel to the axis of the cradle so that the rotational movement of the cradle will produce a lateral feed of the cutter in a direction substantially 55 perpendicular to the side surface of the tooth of the work. This can be achieved readily with a grooving tool whose cutting blades have active side surfaces of zero pressure angle and for that 60 reason such a tool is employed where possible. It is entirely practical to use blades of zero pressure angle for cutting one side of the teeth of a shaving gear, the concave side surfaces of a spiral bevel or hypoid gear for instance, but it is not always feasible to use a cutter having cutting edges 65 of zero pressure angle for grooving the opposite side of the teeth of the work, the convex side surfaces of a longitudinally curved tooth shaving gear for instance. This is because where a tool of zero pressure angle is used, the work must be adjusted angularly into the grooving cutter by the amount of the pressure angle of its tooth surfaces. On the convex sides of the teeth of spiral bevel or hypoid gears in most instances, that is, 70 except where the work diameter is small, this

would be impossible without interference between the work and the grooving cutter. For grooving one side of the teeth of a shaving gear, then, the convex side of a longitudinally curved tooth shaving gear, for instance, a grooving cutter having 5 blades whose active side surfaces are of positive pressure angle will ordinarily be required. In order that the feed of the cutter into the sides of the tooth surfaces of the work may be as nearly as possible in a direction perpendicular to the 10 sides of the teeth of the work, however, it is desirable to keep the pressure angle of the sides of the blades of the grooving tool as small as possible.

The grooves in the side surfaces of the blades of 15 the grooving cutter may be of any desired shape. A preferable construction is to provide the blades with grooves having parallel sides and it is preferred to have these grooves arranged so that the sides of the grooves lie in planes perpendicular to the axis of the cutter, that is, parallel to the direction of cut. Such a grooving cutter will 20 cut grooves in the side surfaces of the shaving gear which will have parallel sides perpendicular to or approximately perpendicular to the sides 25 of the shaving gear. It is also within the scope of the invention to make the grooves in the grooving cutter blades of other shape. Thus, the 30 grooves might be made V-shaped or dove-tailed in shape, that is, with the sides of the grooves undercut, and, where the grooving cutter has blades whose active sides are of positive pressure angle, the grooves in said sides of the blades may extend either perpendicular to the axis of the cutter or at any desired angle thereto.

Reference will now be had to the drawings for a more detailed description of the invention. Here, I have shown how a gear cutting machine of the type covered by U. S. Patent No. 1,724,241 of August 13, 1929, may be modified to practice 40 the present invention in the grooving of a longitudinally curved, tooth shaving gear of spiral bevel or hypoid gear form having non-generated side tooth surfaces.

The shaving gear blank is designated at G. It 45 is a previously, finish-cut non-generated spiral bevel or hypoid gear having longitudinally curved teeth of straight profile shape. The shaving gear blank is secured to the work spindle of the machine in the usual or in any suitable manner. 50 The work spindle is journaled in the usual manner upon the work head 10 of the machine. The work head has the usual linear and angular adjustments on the swinging base 71 of the machine for adjusting the work into operative position. The means for effecting these adjustments have not been shown but may correspond to those illustrated in my prior patent above mentioned. Ordinarily, it is not required to offset the axis of the work from the axis of the cradle to groove 60 shaving gears by the process of the present invention and hence the vertical adjustment of the work head described in the prior patent above mentioned, may be omitted in a machine for practicing the present invention and, hence, a 65 work head without adjustment for offset of the work spindle is illustrated in the accompanying drawings. Such a work head corresponds to the type ordinarily employed on Spiral Bevel Gear Generators.

The grooving tool here shown is of the face-mill type and is denoted at C. It is secured in any suitable manner to the cutter spindle 12 which is journaled on anti-friction bearings 13 and 14 in a saddle 15.

The cutter spindle is driven from a motor 16 through bevel gearing 17, 18, a shaft 19 to which the bevel gear 18 is secured, a pair of spur gears (not shown) which connect the shaft 19 with a parallel shaft (not shown), a bevel gear (not shown) carried by the latter shaft, a bevel gear 20 which is driven by the last named bevel gear, the shaft 21 to which the bevel gear 20 is secured, the spur pinion 22 which is integral with the shaft 21, and the internal gear 23 which is secured to the enlarged end face or seat portion 24 of the cutter spindle. All of the parts mentioned are mounted upon the saddle 15.

The saddle 15, as will be described more fully hereinafter, is mounted upon a plate 26 for step-by-step movement in a direction axial of the cutter spindle. The saddle is guided in this movement by a way 25 which is formed upon the plate 26 and the saddle is held upon the plate by the 20 gib 27 which is secured to the plate by screws 28.

The plate 26, as described in the patent above mentioned, is angularly adjustable upon a slide 30 about an axis perpendicular to the axis of the cutter spindle. This adjustment is ordinarily 25 not used in practicing the present invention. The slide 30 is adjustable vertically upon a column 32, through rotation of the screw shaft 33 which is rotatably mounted in the column and threads into a nut (not shown) which is secured to the 30 back of the slide 30.

The column 32 is adjustable angularly upon a plate 35 about an axis at right angles to the axis about which the adjustment of the plate 26 is made. This adjustment, too, is ordinarily not 35 employed in practicing the present invention. The plate 35 is adjustable laterally upon the cradle 36 by a screw shaft 37 which is journaled in the plate 35 and threads into a nut (not shown) which is secured to the upper face of 40 the cradle. The column 32 and plate 35 are secured to the cradle after adjustment by T-bolts 38.

The various adjustments referred to and the means for making the same are described more 45 fully in my prior patent above referred to and reference may be had to that patent for a more detailed description of the same.

The cradle is formed, as in the machine of my prior patent, with arcuate guide surfaces 40 which seat on ways 41 formed on the base or frame 41 of the machine. The cradle has an oscillatory movement, as in the machine of my prior patent, and this movement is produced by a worm 43 which meshes with worm wheel 44 which is secured by screws 45 to the cradle.

The drive to the cradle may be the same as in my prior patent. This drive is, however, disconnected from the drive to the work spindle in the preferred practice of the present invention so that during the actual cutting of the grooves in the side surfaces of the teeth of the shaving gear, the work spindle does not have a rotary motion but remains stationary. The only drive to the work spindle is that employed for indexing the work from tooth to tooth. The indexing mechanism may be similar to that employed in the machine of my prior patent and only the final members of the indexing drive are illustrated in the accompanying drawings, namely, the worm 50 and the worm wheel 51.

The grooving cutter may have blades with a single cutting land or rib, but preferably the blades of the grooving cutter are grooved to provide a plurality of cutting lands, as shown in the cutter illustrated in the drawings, so that the

whole side surface of a tooth of the work can be grooved at one time. The latter type of cutter is shown in the drawings. This cutter has cutting blades B which have parallel grooves 55 in their side faces that extend from the front to the back of the blades, as illustrated in Fig. 7, and are spaced from one another on the blades in the direction of the height of the blades.

The grooves are preferably cut into the sides of the blades so that they extend in a direction 10 perpendicular to the axis A of the cutter and are preferably made, as shown in Figs. 4 and 5, so that they have parallel sides.

It is possible to cut grooves in only one side of the teeth of the shaving gear at a time. In Fig. 15 4, I have shown a cutter whose blades have grooves in their outside surfaces for cutting grooves in the concave sides of the teeth of the work. In Fig. 5, I have shown a cutter C' for grooving the convex sides of the teeth of the work. This cutter has grooves formed on the inside surfaces of the blades. If the same cutter is to be used for grooving both sides of the teeth of the work, both sides of its blades should be grooved. Only one side of the teeth of the work 25 can be grooved at a time and the cutter must be readjusted relative to the work to groove the opposite sides of the teeth of the work.

Preferably, different cutters are employed for grooving the opposite sides of the teeth of the work. Where separate cutters or separate blades are used for grooving the opposite sides of the teeth of the work, the inactive sides of the blades may be left smooth, as shown in the case of the inactive sides of the blades illustrated in Figs. 35 4 and 5.

To groove a shaving gear of spiral bevel or hypoid form on a machine built to practice the present invention, the work and grooving tool are adjusted relative to one another as in setting up a machine to cut a spiral bevel or hypoid gear.

Fig. 4 illustrates the relative positions of a gear G, which is to be grooved, and a cutter C of preferred form for the grooving of the concave sides of the teeth of such gear G. The tool C shown in Fig. 4 has blades 60 which have grooved outside surfaces which are of zero pressure angle, that is, which are parallel to the axis A of the cutter. The gear G must, accordingly, 50 be adjusted relative to the cutter in accordance with the pressure angle α of the concave sides 61 of the teeth 62. This angular adjustment can be effected in the usual manner by lateral and vertical adjustment of the cutter and by slight modification in the root angle setting of the work.

In Fig. 5, I have shown the work gear G adjusted relative to the cutter C' which is to groove the convex sides 63 of the teeth 62 of the gear. Here a cutter C' is used whose cutting edges have a slight positive pressure angle α' .

In the operation of the machine illustrated, the cutter rotates continuously on its axis; the work is fed into operative relation with the cutter by operation of the feed cam 70 which is connected 65 in the usual manner, as shown in my patent above mentioned, to the swinging base 71; after the work is in operative position, the cradle is oscillated in one direction to feed the grooving cutter sidewise into the side of a tooth of the work; when the grooves in the side of the tooth have been cut to the desired depth, the direction of roll of the cradle is reversed to withdraw the cutter sidewise from the work and return the cradle to its original position; when the cutter 75

clears the side of the teeth, the work is withdrawn from operative position by operation of the feed cam 70; and then the work is indexed. Then the cycle begins anew. During cutting, the work is held stationary as above described.

Figs. 4 and 5 illustrate diagrammatically how oscillatory motion of the cradle operates to produce the sidewise feed and withdrawal movements of the tool with reference to the work. 10 75 denotes the axis of the cradle. It will be noted that the axis of the cutter is parallel to the axis of the cradle, but is offset therefrom, that is, it is eccentric to the axis of the cradle. Hence, as the rotating cutter is swung about the axis 15 of the cradle, the axis A or A' of the cutter will travel on a circle whose center lies on the axis 75 of the cradle. Thus, the cutter is moved bodily toward and into the sides of a tooth of the stationary work as it is swung in one direction 20 and is withdrawn bodily away from the side of the tooth as it is swung in the opposite direction by the oscillatory movement of the cradle. Through the operation of the machine, grooves 25 71 are cut in the concave sides 61 of the teeth 62 of the shaving gear, as shown in Fig. 6 and grooves 73 may be cut in the convex sides 63 of the teeth.

The direction of lateral feed movement of the cradle for the cutting of the convex side of the 30 teeth of the shaving gear is reversed with reference to the direction of lateral feed movement of the cradle for cutting the concave sides of the teeth. Thus, as indicated in Fig. 4, the cradle is swung about its axis 75 to move in the direction 35 denoted by the arrow 77 to feed the cutter C sidewise into the concave sides of the teeth of the work G and is withdrawn by swinging the cradle back in the opposite direction as denoted by the arrow in 78, while in the cutting of the 40 convex sides of the teeth of the work, the lateral feed movement is in the direction denoted by the arrow 78' in Fig. 5 and the withdrawal movement is in the direction of the arrow 77'.

As will be clear from Fig. 5, if the work gear 45 G is of large diameter, it would interfere with the cutter C' if the work were adjusted angularly to the pressure angle of its teeth. Accordingly, for the grooving of the convex sides of the teeth of a shaving gear, it is desirable to use a cutter, such as shown in Fig. 5, having cutter blades 65 whose inside surfaces have a slight pressure angle α' . This pressure angle should be kept as low as possible so that the grooves and lands on the inside surfaces of the 50 blades may cut as nearly as possible in a direction perpendicular to the convex sides 63 of the gear teeth in their lateral in-feed movement.

It is desirable, as pointed out in the copending application of Witham above mentioned, to have the grooves in corresponding sides of a shaving gear staggered or displaced with reference to one another so that the cuts made by one tooth of the shaving gear are not merely repeated by another tooth of the shaving gear and a smoother finish may be produced on the sides of the gear 60 by the shaving. The machine illustrated in the drawings of the present application is provided with a mechanism for automatically shifting the grooving cutter axially between cutting of the 65 corresponding sides of successive teeth of the work so as to produce this desired displacement of the grooves on corresponding sides of successive teeth of the shaving gear. This mechanism will now be described.

As above stated, the saddle 15 is mounted on

the plate 26 for movement axially of the cutter spindle. Secured to the plate 26 by screws 80 is a box or housing 81 in which there is journaled a screw shaft 82 which threads into a nut 83 that is integral with a cover-plate 84. 5 The cover-plate 84 closes the bore in the saddle in which the cutter spindle and its bearings are mounted and the cover-plate is secured in position by screws not shown. The screw shaft 82 is rotated step by step, being advanced or withdrawn, each time when the work is indexed, thus advancing or withdrawing the cutter axially so that the positions of the cutter, during the grooving of corresponding sides of successive teeth of the work, are displaced axially from one another. 10 15

The mechanism for intermittently rotating the screw shaft 82 comprises a solenoid 85, the core-bar 86 of which is connected by a link 87 with a bell crank lever 88. The lever 88 is oscillatably mounted upon a shaft 89 which is journaled in the box 81 parallel to the screw shaft 82.

The bell crank lever 88 carries a pawl 90 which is pivotally mounted upon the lever by means of the pin 91. The pawl is adapted to engage the teeth of a ratchet-wheel 92 which is keyed to the shaft 89. The pawl is held in engagement with the teeth of the ratchet wheel by a coiled-spring 94 that may be disengaged therefrom by rotating the cam-member 95 about its pivot pin 96. The cam-member is adapted to engage the tail of the pawl.

As will be seen, each time that the solenoid 85 is energized, the core-bar 86 is moved to the left from the position shown in Fig. 3, thus oscillating the crank 88 and causing the pawl 90 35 to advance the ratchet wheel. There is a spur gear 98 mounted on the shaft 89 and having a splined connection thereto. This spur gear meshes with a spur pinion 99 which is secured to an idler-shaft 100 that is journaled in a 40 quadrant arm 102. The arm 102 is adjustably mounted upon a box 81 by means of a bolt 103 which passes through an elongated slot 104 in the arm.

There is a spur gear 105 secured on the idler 45 shaft 100 and this spur gear meshes with a spur gear 106 which has a splined connection with the screw shaft 82. Thus, when the solenoid 85 is energized, rotation is imparted to the screw shaft 82.

Any suitable means may be employed for energizing the solenoid once for each cycle of operation of the machine. In the machine illustrated, there is a lug 110 adjustably secured by a T-bolt 111 in a circular slot 116 in one face of 55 the feed cam 70. The feed cam is geared to make one revolution for each feed and withdrawal movement of the work, that is, for each cycle of operation of the machine. There is a lever 112 pivotally mounted at 113 on the base 60 of the machine. This lever carries a roller 114 in position to be engaged by the lug 110 as the lug is carried around by the rotation of the cam 70.

A lever 115 is also secured to the shaft 113. This lever is arranged so that when it is rocked clockwise it operates a switch 117 that is electrically connected by means of the line 118 with the solenoid 85. The switch 117 is a normally 70 open switch.

The shaft 113 may also carry the lever 120 for operating the automatic stopping mechanism 122 of the machine. This, however, forms no part of the present invention. The switch 117 75

may be secured to one side of the automatic stopping mechanism, as shown.

The solenoid 85 is so mounted that the core-bar 86 is vertical and drops down by gravity 5 when the solenoid is de-energized.

With the mechanism described, it will be seen that the solenoid is energized once for each cycle of operation of the machine and the lug 110 may be so adjusted on the cam 70 that energization 10 of the solenoid takes place in the indexing interval. When the solenoid is energized, the screw shaft 82 is rotated to advance or withdraw the cutter axially. Thus the cutter will have a different position when cutting successive corresponding tooth sides of the work and so the 15 grooves formed in successive corresponding sides of the teeth of the work will be displaced depthwise with relation to one another.

The direction of rotation of the screw shaft 20 depends upon the gearing employed between the ratchet wheel 92 and the screw shaft and upon the hand of the screw thread. In Fig. 6, the grooves in successive teeth are displaced relative to one another toward the bottoms of the tooth 25 slots. 62' designates the first tooth cut, 62², the second tooth and 63³, the third tooth cut. It will be noted that the grooves in corresponding sides of these teeth are successively displaced on the successive teeth toward the bottoms of 30 the tooth spaces.

The screw shaft 82 may be adjusted to position the cutter at correct depth prior to a cutting operation by rotation of the shaft itself by a suitable wrench and for this purpose the 35 shaft at its outside end will have a hexagonal head, as illustrated in Fig. 2. A graduated dial 125 is secured to the screw shaft to permit initial adjustment of the shaft to be made accurately. This dial is adapted to read against a zero mark 40 on the box 81.

A friction brake comprising a spring-pressed plunger 126 of some suitable friction material serves to hold the ratchet wheel 92 against the backward movement. This plunger is housed 45 in a sleeve 127 that is adjustably threaded into the box 81.

Due to the displacement of the cutter between grooving of successive teeth, the grooves in the successive teeth are arranged in a helix. If the displacement is continuous for the cutting of the grooves in all of the teeth, then corresponding grooves of the teeth will be arranged in a single lead. If the cutter is readjusted axially after the cutting of a certain number of teeth, then 50 corresponding grooves of the teeth will be arranged in several leads or threads.

In the drawings, the grooving cutters have been shown as provided with blades which have parallel sided grooves that extend in a direction 55 perpendicular to the axis of the cutter. It will be understood, however, that the blades might be provided with grooves which are parallel sided but which are inclined to the axis of the cutter if the proper direction of relative feed is used. It is also to be understood that the grooves 60 might be of V-shape and extend either parallel to the axis of the cutter or inclined thereto. Likewise, the grooves might be of dove-tail shape so that the sides of the groove would be undercut with reference to the side surfaces of the 65 blades. Other modifications will readily suggest themselves to those skilled in this art.

While the invention has been described in connection with a machine, process, and tools for 70 cutting grooves in the side faces of spiral bevel

and hypoid shaving gears, it will be understood that broadly this invention is applicable also to the grooving of other types of shaving gears. Grooves in straight bevel or spur gear shaving tools might be produced, for instance, with planing tools having grooved side faces which are fed laterally into the sides of the teeth of the shaving gear. For straight bevel gears, the lateral feed movement might be produced as in the machine herein described, namely, by rotation of 10 the cradle upon which the planing tool is mounted while the work is held stationary. This operation can be performed upon a standard straight bevel gear generating machine by disconnection of the generating drive of the work spindle and 15 modification of the machine in a manner similar to that illustrated in the drawings of the present application. Other modifications and uses of the invention will be apparent to those skilled in the art. The present application is intended to cover 20 any adaptations, uses, or embodiments of the present invention following, in general, the principles of the invention and including such departures from the present disclosure as come within known or customary practice in the gear 25 art and as may be applied to the essential features hereinbefore set forth and as fall within the scope of the invention or the limits of the appended claims.

Having thus described our invention, what we 30 claim is:

1. The method of grooving a shaving gear which comprises employing a cutting tool which has a side surface that is provided with a plurality of grooves spaced in the direction of active 35 height of the tool and a serrated side cutting edge formed at the juncture of said side surface and the front face of the tool, engaging said tool with the gear so that it extends into a tooth space of the gear, and moving said tool longitudinally of the tooth space while producing a relative sidewise feed movement between the tool and gear to feed the tool sidewise into one side of the tooth space to cut simultaneously a plurality of 40 grooves therein.

2. The method of producing a shaving gear which comprises employing a cutting tool that has a serrated side surface and a side cutting edge formed at the juncture of said side surface and the front face of the tool, engaging said tool with a gear so that it extends into a tooth space 45 of the gear and moving said tool longitudinally of the tooth space while holding the gear stationary and producing a relative feed movement between the tool and gear about an axis inclined to the axis of the gear and parallel to the described side surface of the tool to feed the tool laterally into one side surface of the tooth space to cut simultaneously a plurality of grooves 50 therein.

3. The method of producing a shaving gear which comprises grooving each tooth of the gear by moving a grooving tool longitudinally across a side of a tooth while producing a relative feed movement between the tool and gear sidewise of 55 the gear tooth, indexing the gear periodically and adjusting the tool between the grooving of corresponding sides of different teeth of the gear so that the grooves produced on successive teeth will be displaced progressively relative to one 60 another in the direction of depth of the teeth of the gear.

4. The method of producing a shaving gear which comprises employing a ribbed cutting tool having a serrated cutting edge of zero pressure 65

- angle, adjusting a previously formed gear into engagement with the tool so that a side surface of a tooth of the gear is parallel to the edges of the cutting ribs of the tool, moving the tool across the side of the tooth from one end thereof to the other, and producing relative rotary movement between the tool and gear about an axis parallel to the described side of the tool to feed the tool laterally into the gear.
5. The method of producing a shaving gear which comprises employing a ribbed cutting tool having a serrated cutting edge of zero pressure angle, adjusting a previously formed gear relative to the tool so that a side of a tooth of the gear is parallel to the edges of the cutting ribs, moving the tool along the side of the tooth of the gear from one end thereof to the other while producing a relative rotary movement alternately in opposite directions between the tool and gear about an axis parallel to said side of the tool to feed the tool laterally into the side of the gear tooth, indexing the gear periodically, and adjusting the tool in the direction of said axis between the cutting of different teeth of the gear 25 so as to displace the grooves on different teeth of the gear relative to one another in the direction of depth of the teeth.
6. The method of producing a shaving gear which comprises employing a face-mill cutting tool having blades which have a ribbed side surface and a cutting edge formed at the juncture of said side surface with the front face of the blade, and rotating said tool with a gear while producing a relative feed movement between the 30 tool and the gear laterally into a side of a tooth of the gear.
7. The method of producing a shaving gear which comprises employing a face-mill cutting tool having blades each of which has a ribbed 35 side surface and a side cutting edge formed at the juncture of said side surface with the front face of the blade, and rotating said tool in engagement with a gear while producing a relative feed movement between the tool and gear about an axis parallel to the tool axis.
8. The method of producing a shaving gear which comprises employing a rotary face-mill cutting tool having a ribbed side surface which is parallel to the axis of the tool and a side cutting edge formed at the juncture of said side surface with the front face of the tool, adjusting a previously toothed gear so that a side surface 40 of a tooth of the gear is parallel to the axis of the tool, moving the tool across the side of the tooth from one end thereof to the other, and producing a relative lateral feed movement between the tool and gear in a direction perpendicular to the side of the tooth.
9. The method of producing a shaving gear which comprises employing a rotary face-mill cutting tool having blades which have a ribbed side surface which is parallel to the axis of the tool and a side cutting edge formed at the juncture of said side surface with the front face of the blade, adjusting a previously toothed gear so that a side of a tooth of the gear is parallel 45 to the axis of the tool, rotating the tool with the gear and while holding the blank stationary, and simultaneously producing a relative rotary movement between the tool and gear about an axis parallel to but offset from the cutter axis to produce a lateral feed movement between the tool and gear in a direction substantially perpendicular to the side of the tooth of the gear.
10. In a machine for grooving shaving gears,
5. a cutting tool having a side face provided with a plurality of alternate grooves and lands and a serrated side cutting edge formed at the juncture of said side face with the front face of the tool, means for moving the tool longitudinally across the face of a gear, means for relatively moving the tool into and out of operative engagement with the gear, means for producing alternately lateral feed and withdrawal movements between the tool and gear sidewise of a tooth of the gear 10 when the tool is in engagement with the gear, and means for indexing the gear when the tool is out of engagement.
11. In a machine for grooving shaving gears, a face-mill cutting tool having blades with side surfaces which are provided with alternate grooves and lands extending from front to rear of the blades and a side cutting edge formed at the juncture of said side surface with the front face of the blades, means for rotating the tool with the gear, means for producing alternately lateral feed and withdrawal movements between the tool and gear sidewise of a tooth of the gear, and means for indexing the gear periodically 20 when the tool is withdrawn.
12. In a machine for grooving shaving gears, a face-mill cutting tool having blades with serrated side cutting edges whose side surfaces are provided with alternate grooves and lands, means for rotating the tool with the gear, and means for producing a relative oscillatory movement between the tool and gear about an axis parallel to the axis of the tool to produce a lateral feed movement between the tool and gear sidewise of a tooth of the gear.
13. In a machine for grooving shaving gears, a face-mill cutting tool having blades which have serrated side cutting edges and side surfaces formed with alternate lands and grooves, means for rotating said tool with a gear, means for producing a relative oscillatory movement between the tool and gear about an axis parallel to the axis of the tool to produce alternately lateral movements of feed and withdrawal between the tool and gear in a direction substantially 40 perpendicular to a side of a tooth of the gear, means for indexing the gear periodically when the tool is out of engagement with the gear, and means for displacing the tool axially between cutting of successive teeth of the gear so that the tool has a different axial position in cutting successive teeth of the gear.
14. The method of grooving the teeth of a shaving gear which comprises cutting grooves in the sides of different teeth of the gear by actuating a cutting tool in the lengthwise direction of a groove to be cut while producing a relative lateral feed movement between the tool and gear to cut the groove to the desired depth in a side of a tooth of the gear and withdrawing the tool from engagement with the gear and indexing the gear after the desired grooving operation has been performed on one tooth, and then bringing the tool back into operative position and repeating the operation to groove the new tooth, and shifting the position of the tool depthwise of the gear teeth between the cutting of grooves in different teeth of the gear so that said grooves are displaced depthwise relative to one another.
15. The method of grooving the teeth of a 70 shaving gear which comprises cutting grooves in the sides of different teeth in the gear by rotating a face-mill gear cutter, having a plurality of cutting blades and which has cutting lands formed on the side faces of its blades, in engagement 75

with a gear while producing a relative lateral feed movement between the tool and gear to cut a groove of the desired depth into a side of a tooth of the gear, and withdrawing the tool from engagement with the gear and indexing the gear after the desired grooving operations have been performed on one tooth, then returning the tool into engagement with the gear and repeating the operation to groove the new tooth, and displacing the tool axially between the grooving of different teeth of the gear so that the grooves of different teeth are displaced relative to one another in the direction of tooth depth.

16. The method of grooving the teeth of a shaving gear which comprises cutting grooves in the sides of different teeth in the gear by rotating a face-mill gear cutter which has a cutting land formed on each cutting blade, in engagement with a gear while producing a relative feed movement between the tool and gear about an axis parallel to but offset from the cutter axis to cut a groove of the desired depth into a side of a tooth of the gear, and withdrawing the cutter from engagement with the gear and indexing the gear after the desired grooving operations have been performed on one tooth, then returning the cutter into engagement with the gear and repeating the operation to groove a new tooth, and displacing the cutter axially between the cutting of different teeth of the gear so that said grooves are displaced relative to one another in the direction of tooth depth.

17. The method of grooving the teeth of a shaving gear which comprises cutting grooves in the sides of different teeth of the gear by rotating a face-mill gear cutter which has a cutting land formed on each of its cutting blades, in engagement with a gear while producing a relative feed movement between the tool and gear about an axis parallel to the cutter axis and parallel to the cutting edges of said lands to cut a groove to the desired depth into a side of a tooth of the gear, and withdrawing the tool from engagement with the gear and indexing the gear after the desired grooving operations have been performed on one tooth, then returning the tool into engagement with the gear and repeating the operations to groove a new tooth, and displacing the tool axially between cutting of different teeth of the gear so that the grooves cut in different teeth are displaced relative to one another in the direction of tooth depth.

18. A machine for grooving the teeth of shaving gears comprising a work support, a tool support, a tool movably mounted on the tool support, means for actuating the tool in the lengthwise direction of a groove to be cut, means for simultaneously producing a relative feed movement between the tool and gear to cut a groove of the desired depth in a side of the tooth of the gear, means for periodically indexing the gear, and means for varying the depthwise position of the tool relative to the gear between the cutting of grooves on different teeth of the gear

so that the grooves of different teeth will be displaced depthwise relative to one another.

19. A machine for grooving the teeth of a shaving gear comprising a work support, a tool support, a tool movably mounted thereon, means for moving the tool longitudinally along the teeth of a gear, means for simultaneously producing a relative feed movement between the tool and gear laterally of a side of a tooth to cut a groove of the desired depth in the side of said tooth, means for periodically indexing the gear, and means for displacing the tool in the direction of tooth depth between the cutting of grooves on different teeth of the gear so that the grooves of different teeth will be displaced relative to one another.

20. A machine for grooving the teeth of a shaving gear comprising a work support, a tool support, a face-mill gear cutter journaled in said tool support which has a cutting land formed on a side of each of its blades, means for rotating the cutter in engagement with a gear, means for simultaneously producing a relative lateral movement between the tool and gear to cut grooves of the desired depth in the sides of the teeth of the gear, means for periodically indexing the gear, and means for displacing the cutter axially between the grooving of different teeth of the gear so that the grooves cut therein will be displaced relative to one another.

21. A machine for grooving the teeth of a shaving gear comprising a work support, a tool support, a face-mill gear cutter journaled in said tool support which has a cutting land formed on a side of each of its blades, means for rotating the cutter in engagement with the gear, means for simultaneously producing a relative movement between the cutter and gear about an axis parallel to the cutter axis to cut grooves of the desired depth in the sides of the teeth of the gear, means for periodically indexing the gear, and means for displacing the cutter axially between the grooving of different teeth of the gear so that the grooves cut therein will be displaced relative to one another.

22. A machine for grooving the teeth of a shaving gear comprising a work support, a tool support, a face-mill gear cutter journaled in said tool support which has a cutting land formed on a side of each of its blades, means for rotating the cutter in engagement with the gear, means for simultaneously producing a relative movement between the cutter and gear about an axis parallel to the cutter axis and parallel to the cutting edges of the cutting lands to cut grooves of the desired depth in the sides of the teeth of the gear, means for periodically indexing the gear, and means for displacing the cutter axially between the grooving of different teeth of the gear so that the grooves cut therein will be displaced relative to one another.
